UNITED STATES PATENT OFFICE.

WILLIAM J. BEARDSLEY, OF JACKSON, MICHIGAN, ASSIGNOR OF ONE-HALF
TO GEORGE J. SCHUMACHER, OF JACKSON, MICHIGAN.

TIE FOR BAGS, BALES, OR THE LIKE.

SPECIFICATION forming part of Letters Patent No. 732,673, dated June 30, 1903.

Application filed April 14, 1903. Serial No. 152,599. (No model.)

To all whom it may concern:

Be it known that I, WILLIAM J. BEARDSLEY, a citizen of the United States, residing at the city of Jackson, in the county of Jackson and State of Michigan, have invented certain new and useful Improvements in Ties for Bags, Bales, or the Like, of which the following is a specification.

This invention relates to improvements in a tie for bales, bags, or the like.

The object of the invention is to provide a tying device which is fastened to the bale or bag and is provided with a spring clamping member positioned to grip the cord or bauld between its edge and the base.

A further object of my invention is to provide a tying device which when gripping the string tends to hold the latter tighter as it is relaxed under the influence of the expanding bag.

Many other objects and advantages will be hereinafter referred to and be particularly pointed out in the claims.

In the drawings, Figure 1 is a perspective view of my improved tying device applied to a bag. Fig. 2 is a similar view, the cord being wrapped around the bag and ready to be gripped by the spring clamping member. Fig.

3 is a similar view of the bag tied. Fig. 4 is an enlarged detail perspective view of the tie. Fig. 5 is an enlarged cross-section on the line $\alpha\alpha$, Fig. 4. Fig. 6 is a top plan view. Fig.

7 is a plan view of the blank from which the tie is formed.

The same numerals refer to like parts in all the figures.

1 represents a bag, which may be either a bag used for ordinary purposes or may be of the type utilized in forming a bale.

2 indicates my improved tie, and it consists of a base 3, having openings 4, through which rivets 5 are passed to fasten it to the bag 1, and 6 is an opening near one end of the base to receive a cord or the like.

7. A reduced extension or neck projects from the opposite end of the base 3, and it is provided at its outer end with a spring clamping member 10, formed at one end with a finger-grip 11. The neck 9 is bent to cause the spring member 10 to incline slightly in relation to the base in such manner that the

edge 12 will press the base. The forward end 13 of the edge 12 is slightly beveled to allow of the convenient introduction of the cord 7.

In operation the tie and its cord are a fixture with the bag, and in order to secure the latter the cord is wrapped around the upper end several times, as clearly shown in Fig. 2, whereupon the cord is passed between the beveled end of the edge 12 and the base 3 until it encounters the neck 9. Immediately the end of the cord is released its tendency is to relax, and it is this action which causes the edge to grip it between itself and the base, so that the greater the pull backward the tighter the edge grips. This action is due to the peculiar angle of the clamping member 10 with relation to the base 3, it being evident that the cord once positioned it is bound to be securely fastened. The gripping action is further augmented by the relationship between the neck and the angle of the member 10. A sharp turn is given the cord around the neck, which releases the strain somewhat, hence rendering it practically impossible for the strain of the cord to overcome the clamping action of the edge 12.

To untie a bag, it only requires a slight pull of the cord in the direction of the angle of the member 10 and then off to one side toward the beveled edge 13, when it is readily released and the bag may be unwrapped.

For convenience and further to better enable the spring member 10 to grip I prefer to use a flat cord. However, I do not desire to limit myself to this precise detail of construction.

My invention is extremely simple and durable in construction and enables me to tie and untie bags or the like conveniently and quickly without the use of severing the cord. Furthermore, the whole device being fixed to the bag saves labor and loss of time when a bag is to be tied.

What I claim as new is—

1. A tie for a bag or bale, comprising a base, a spring clamping member having its edge in contact with the base, and a cord secured to the base and adapted to be held between said base and the edge of the clamping member, substantially as described.

2. A tie for a bag or bale comprising a base,

a clamping member positioned at an angle to the base to present one edge of said member to said base, a cord, and means for causing the edge of the clamping member to grip the cord on the base, substantially as described.

5. 3. In a bag or bale tie, the combination with a base fastened to a bag, a cord secured to the base, and a spring clamping member formed with the base and bent to present its edge 10 against the base, whereby the cord may be clamped between the said edge and the base as it tends to pull back, substantially as described.
10. 4. A tie for bags or bales, comprising a base,

a reduced neck at one end of the base, a 15 spring clamping member formed on the neck and having its edge bearing on the base, and a cord adapted to be engaged between the edge and the base and be limited in its movement by the neck, substantially as described. 20

In testimony whereof I have signed my name to this specification in presence of two witnesses.

WILLIAM J. BEARDSLEY.
